[57] CLAIM

The ornamental design for an emergency flasher, as shown and described.

DESCRIPTION

FIG. 1 is a front elevational view of the emergency flasher showing our new design;

FIG. 2 is a top view of the emergency flasher of FIG. 1; FIG. 3 is a rear view of the emergency flasher of FIG. 1;

FIG. 4 is a bottom view of the emergency flasher of FIG. 1; and

FIG. 5 is a right side view of the emergency flasher of FIG. 1.

The indicia shown in broken lines in FIG. 1 is for illustrative purposes only.
